ALBERT H. DE VOE, OF WESTFIELD, NEW JERSEY, ASSIGNOR TO THE SINGER MANUFACTURING COMPANY, A CORPORATION OF NEW JERSEY.

FABRIC-DRAWING DEVICE FOR SEWING-MACHINES.

1,251,353.

Specification of Letters Patent. Patented Dec. 25, 1917.

Application filed April 27, 1914. Serial No. 834,655.

To all whom it may concern:

Be it known that I, ALBERT H. DE VOE, a citizen of the United States, residing at Westfield, in the county of Union and State 5 of New Jersey, have invented certain new and useful Improvements in Fabric-Drawing Devices for Sewing-Machines, of which the following is a specification, reference being had therein to the accompanying drawings.

This invention relates to improvements in fabric drawing devices for sewing machines, adapted to handle the work when it leaves the machine after the stitch-forming operation, 15 acting to pull away the stitched fabric so that the feeding mechanism of the machine may not be required to push against the inert folds. The device is adapted for use in connection with machines for seaming long strips of bunting, canvas and the like, 20 in which the stitching mechanism usually operates at very high speed and the strips of material are fed so rapidly through the machine that it has been customary for an operator to constantly draw away the finished material at the rear of the machine 25 to relieve the feed-dog from acting against the inertia and weight thereof.

By the present invention the stitched material is drawn away as soon as any slack in the same appears at the rear of the machine, the device comprising feeding elements of such form and arrangement that pull upon that portion of the material resting 35 on the work-plate of the machine is wholly avoided so as not to interfere with the action of the stitch-forming elements.

The invention comprises a positively driven feed-roller mounted between spaced standards rigidly connected by means of a series of connecting rods, said roller acting in conjunction with an overlying idler-roller provided with an axial shaft which projects slightly beyond each end thereof and within 45 an open slot formed in the top of each standard. The idler-roller is supported for movement toward and from the driven roller, and for this purpose each end of its shaft is journaled within the bearing boss of a supporting arm pivotally connected at its lower end to the lateral arm of a lifting lever disposed adjacent each standard, the two levers being rigidly connected by means of upper and lower connecting rods, the upper rod being 55 journaled within bearing apertures formed

in the standards. In practice, the device is secured to the work-table at the rear of a sewing machine, and the stitched fabric is led beneath the lower connecting rod for the lifting levers and thence between the feed-rollers, the shaft of the driven roller being provided with a grooved driving wheel having a belt connection with the main-shaft of the sewing machine. Slack in the stitched fabric will be drawn up by the action of the feed-rollers, but immediately thereafter the moving fabric will elevate the lifting levers for the upper roller and the device will become ineffective until sufficient fabric is advanced through the sewing machine to again form slack whereupon the lifting levers and the connected idler-roller will move downward and the rollers will act to draw the slack from the work-table.

From the above it will be seen that the device is controlled by the fabric itself to act automatically when the necessity arises. It will also be seen that the device is ineffective to exert a pull upon that portion of the fabric being acted upon by the stitch-forming mechanism of the machine.

In the drawings, Figure 1 is a side elevation of the improvements applied to a sewing machine, showing by full and dotted lines the two positions of the idler-roller. Fig. 2 is a perspective view of the improvements; and Figs. 3 and 4 are detail views of certain features of the improvements.

As shown in the drawings, the feeding elements are supported by a frame comprising the parallel standards 1, each provided with a base-plate 2 formed with apertures 3 to receive fastening screws for securing the device to the work-table at the rear of a machine. Each standard is formed with a series of transverse bosses 4 adapted to receive the connecting rods 5 by means of which the standards are rigidly connected to afford a supporting frame for the feeding elements. In its upper end each standard is formed with an aperture to receive the axial shaft 6 of a feed-roller 7, one end of said shaft extending beyond the outer walls of its standard and having clamped thereon by means of screw 8 the grooved driving wheel 9. The driving wheel may be connected with the main-shaft of a sewing machine S by means of the belt b, as illustrated in Fig. 1, or may receive its power by other means, as desired. Over-

lying the feed-roller 7 is an idler-roller 10 provided with an axial shaft 11 which projects beyond each end of the roller and between the opposed walls of an open slot 1^x formed in the upper end of each standard 1. As hereinbefore stated, means are provided for elevating and for lowering the idler-roller 10 during the feeding of the material. The means in question include the supporting arms 12, one arm being disposed adjacent each of the standards 1 and intermediate the inner face of said standard and the idler-roller 10, and being provided with a bearing boss 12^x to receive the axial shaft 11 of said roller. The lower end of each arm 12 is apertured to receive a stud-screw 13 fitted within a slot 14 formed in the lateral arm 15 of a lifting lever 16 fixed upon a fulcrum rod 17 journaled in the standards 1. The lifting levers 16 are formed with enlarged apertured lower ends to receive a connecting rod 18, the rod and levers being rigidly connected by means of clamping screws 19. It will be seen from the foregoing that the levers 16, connecting rod 18 and fulcrum-rod 17 form a lifting frame for the supporting arms 12 connected thereto and hence serve to control the movements of idler-roller 10, the latter being elevated when the frame is raised and being returned to its normal position when the frame falls into initial position by gravity.

In some cases it will be found desirable to counterbalance the weight of the lifting frame and hence to reduce its pull upon the idler-roller. To this end the fulcrum-rod 17 of the lifting frame projects beyond the outer face of its supporting standard 1 and is embraced by a helical spring 20, one end of said spring being held fast within an aperture in a collar 21 secured in fixed position upon the fulcrum-rod by means of a clamping screw 22 and the opposite end of said spring being held fast within an aperture in a collar 23 loosely mounted upon bearing sleeve 24, which in turn is clamped within an aperture in the standard by means of screw 25. The collar 23 is formed with a threaded aperture to receive a lever pin 26 which is employed to turn the collar and to clamp the same in its adjusted position upon the bearing sleeve 24. It will be seen that the collar 23 may be turned upon the sleeve 24 to wind the spring 20 and thus to cause the latter to exert a torsional force of the desired degree upon fulcrum-rod 17, such force tending to raise the lifting frame.

As shown in Fig. 1, the material *m* is led under connecting rod 18 of the lifting frame and thence between the feed-rollers 7 and 10. As soon as the feeding mechanism of the sewing machine supplies a slack of stitched material the feed-rollers will draw the same from the rear of the machine; but as soon as the slack is taken up by the feed-rollers

the continued movement of the material will exert a pull upon the connecting rod 18 and the same will be raised to elevate the feed-roller 10, whereupon the action of the feed-rollers will cease until a new supply of slack in the fabric permits the lifting frame to drop by gravity into its initial position. By adjusting the spring 20 the operator may increase or decrease the degree of lifting force necessary to elevate the idler-roller. 75

It may be found desirable to adjust spring 20 to so act upon the levers 16 that the latter will pull downwardly upon the idler-roller to increase the pressure of the rollers upon the fabric, which is advantageous when the device is employed in connection with heavy or stiff fabrics. Such adjustment may be obtained by turning the spring in a direction reverse to that in which it is turned to exert a lifting pressure upon the levers, as will be understood without further explanation. It will be seen that a single spring serves to act upon two spaced levers with equal effect and that the lifting force or the pull upon the idler-roller is the same at both ends thereof, which insures proper drawing of the fabric. 80 85 90

The invention is of a character susceptible of various modifications in the form and arrangement of the elements and therefore the same is not limited to the precise embodiment herein shown and described. 95

Having thus set forth the nature of the invention, what I claim herein is:—

1. In fabric drawing devices for sewing machines, the combination with parallel co-operating feed-rollers, of means for moving one of said rollers relatively to the other including a lever extending into the path of movement of and engaged by the fabric and adapted to be operated by changes in the tension produced on said fabric by the action of the feed-rollers. 100 105

2. In fabric drawing devices for sewing machines, the combination with a frame and a feed-roller mounted in said frame, of a second feed-roller adapted to coact with and bodily movable relatively to the first feed-roller, driving means for one of said feed-rollers, a lever connected with said bodily movable feed-roller, and extending into the path of movement of the fabric whereby said lever is automatically operated at intervals. 110 115

3. In fabric drawing devices for sewing machines, the combination with a frame, a feed-roller mounted in said frame and actuating means therefor, of a second coacting feed-roller, movable supporting arms connected to said second feed-roller, lifting levers connected to said supporting arms, and a rod connecting said lifting levers. 120 125

4. In fabric drawing devices for sewing machines, the combination with a frame, a feed-roller mounted in said frame and actn. 130

ating means therefor, of a second bodily movable feed-roller mounted in said frame for coöperation with the first feed-roller, a lever connected with said second feed-
5 roller and extending into the path of movement of the fabric, and a spring connected with said lever and tending to move the same.

5. In fabric drawing devices for sewing
10 machines, the combination with a frame, a feed-roller mounted in said frame and actuating means therefor, of a second coacting feed-roller mounted in said frame, a lever connected with said second feed-roller, a
15 spring connected with said lever and tending to move the same, and means for changing the tension of said spring and for rendering the same ineffective.

6. In fabric drawing devices for sewing
20 machines, the combination with a frame including spaced standards, of a feed-roller mounted in said frame, actuating means for said feed-roller, a second coacting feed-roller, a supporting arm for each end of the
25 second feed-roller, a lever connected to each supporting arm, a rod connecting the lower ends of said levers, a pivotal connection between said levers and the spaced standards, and a spring for exerting a pressure upon
30 said levers.

7. In fabric drawing devices for sewing machines, the combination with a frame, a feed-roller mounted in said frame and actuating means therefor, of a second coacting
35 feed-roller mounted in said frame, levers engaging the ends of one of said rollers, a spring adapted to act upon said levers, and means whereby the action of said spring will be the same with respect to each lever.

40 8. In fabric drawing devices for sewing machines, the combination with a frame, a feed-roller mounted in said frame and actu-

ating means therefor, a second coacting feed-roller, a lever adapted to move one of said rollers relatively to the other, a spring connected to said lever, and means whereby said spring may be adjusted to exert a lifting pressure upon said lever or to exert a pressure upon said lever in the reverse direction.
45

9. In fabric drawing devices for sewing
50 machines, the combination with coöperating feed members between which the fabric is gripped, of means extending into the path of movement of and controlled by the tension of the fabric for varying the spacing
55 apart of said members upon the fabric and thereby controlling their feeding action.

10. In fabric drawing devices for sewing
55 machines, in combination with main feeding mechanism and secondary feeding means, the latter comprising coöperating feeding members between which the fabric is gripped and means including a movable element extending into the path of movement of and controlled by the tension of the
65 fabric, for controlling the feeding action of said gripping members.

11. In a sewing machine, in combination, fabric-feeding means and fabric drawing means, said latter means comprising fabric-gripping elements adapted to engage the material being operated upon and to pull the same away from the fabric-feeding point, and devices actuated by the fabric tension for varying the fabric-engaging grip of said
75 elements.

In testimony whereof, I have signed my name to this specification, in the presence of two subscribing witnesses.

ALBERT H. DE VOE.

Witnesses:

It is hereby certified that in Letters Patent No. 1,251,353, granted December 25, 1917, upon the application of Albert H. De Voe, of Westfield, New Jersey, for an improvement in "Fabric-Drawing Devices for Sewing-Machines," errors appear in the printed specification requiring correction as follows: Page 3, line 56, claim 9, strike out the words "upon the fabric"; same page, line 62, claim 10, for the word "mempers" read *members*; same page and claim, line 66, for the word "feeding" read *gripping*, and line 67, for the word "gripping" read *feeding*; and that the said Letters Patent should be read with these corrections therein that the same may conform to the record of the case in the Patent Office

Signed and sealed this 26th day of February, A. D., 1918.

[SEAL.]

F. W. H. CLAY,

Acting Commissioner of Patents.
